UNITED STATES PATENT OFFICE.

STEPHEN D. HARTOG, OF ST. LOUIS, MISSOURI, ASSIGNOR, BY MESNE ASSIGNMENTS, TO INLAND MACHINE WORKS, OF ST. LOUIS, MISSOURI, A CORPORATION OF MISSOURI.

METHOD OF MAKING PISTON-RINGS.

1,361,989.

Specification of Letters Patent. Patented Dec. 14, 1920.

Application filed January 24, 1919. Serial No. 272,831.

To all whom it may concern:

Be it known that I, STEPHEN D. HARTOG, a citizen of the United States, residing at the city of St. Louis and State of Missouri, have invented a new and useful Method of Making Piston-Rings, of which the following is a specification.

This invention relates to the art of manufacturing piston rings.

10 An object of the invention is to improve the art of manufacturing piston rings by which rings of an improved and novel construction may be rapidly and economically produced.

15 Another object of the invention is to improve the art of manufacturing piston rings, whereby rings having spaced overlapping end portions which will be pressed together when placed within the piston grooves, and 20 which will also press laterally against the side walls of the grooves to provide a seal, may be economically manufactured.

Other objects will appear from the following description in which reference is 25 made to the drawing illustrating a ring in different stages of manufacture, in which drawings—

Figure 1 is an elevation of a ring blank from which the ring may be constructed.

30 Fig. 2 is an elevation of the ring blank after it has been cut or split circumferentially to a desired extent to provide overlapping ends.

Fig. 3 is an elevation of a finished ring 35 produced by my improved method of manufacture.

Fig. 4 is an elevation of the ring blank shown in Fig. 3 viewed from another side.

Fig. 5 is a view of the ring in connection 40 with a chuck upon which the ring is mounted for treatment.

Fig. 6 is a perspective view of the finished ring, showing also in dotted lines a cutter for cutting the groove in the inner 45 side of the ring.

As illustrated in Fig. 1 the ring blank is of appropriate size to permit a ring of the desired character to be constructed therefrom. As shown in Fig. 2 the ring blank is 50 cut or split circumferentially for a desired distance to provide two overlapping ends separated by a slot 1; and cuts 2 are formed from the ends of the slots to the side edges of the ring blank, thus leaving the overlapping ends free for movement toward and

away from each other as permitted by the resiliency of the metal. As shown in Fig. 3 the cuts 2 are widened to permit compression of the ring and this widening of the cuts may be effected either by removing material from the ends of the overlapping portions or by expanding the ring blank and setting the material in the expanded shape to leave the spaces 2 of sufficient size for the purposes desired. The periphery of the 60 blank is then ground or cut to the proper contour.

Next, the spaced overlapping ends are 65 pressed together and the ring is compressed within a binding ring 3 as shown in Fig. 5 70 and mounted upon an appropriate chuck. When so mounted the overlapping ends of the ring are held pressed together and the ring is held compressed until the ends of the overlapping portions abut against the 75 adjacent shoulders of the ring. Then the side edges of the ring are ground or cut to produce a ring which is of uniform width throughout its circumference, while the overlapping ends are held pressed together 80 in opposition to the resiliency of the material.

Either before or after the ring has been mounted on the chuck as shown in Fig. 5, the ring is cut to form a groove 4 on its inner periphery immediately opposite from the intermediate portions of the overlapping ends. The groove may be of any desired length to render the portion of the ring opposite the overlapping ends properly resilient to permit free movement of the overlapping ends 85 toward and away from each other and without danger of weakening or breaking the overlapping ends from the remaining portion of the ring. It will be understood that 90 the presence of the groove 4 somewhat equalizes the resistance or resiliency of the portion of the ring in which said groove is formed as compared with the resistance or resiliency of the overlapping ends. This is 95 desirable for the purpose of enabling all portions of the ring to yield when the overlapping ends are spread apart or pressed toward each other, so that there is no undue or excessive strain upon any portion of the 100 ring.

After the ring has been finished and removed from the chuck or other fixture in which it may be mounted for treatment, the overlapping ends spread apart to their 110

formed positions as will be understood by reference to Fig. 6 in which it will be seen that the combined width of the overlapping ends plus the space separating them is 5 greater than the width of the opposite portion of the ring in which the groove 4 is formed; but when the ring is compressed and the overlapping ends are pressed together sidewise the combined width of the 10 overlapping ends of the ring is the same as the width of the opposite portion of the ring.

When the ring is placed within the groove of a piston and mounted within a cylinder, 15 the ring is compressed nearly to the position shown in Fig. 5 in which the overlapping ends of the ring are pressed together sidewise, and the ends of the overlapping portions are close to the shoulders on the adjacent portion of the ring. When thus mounted in the groove of a piston and compressed within a cylinder the overlapping ends of the ring press sidewise against the side walls of the piston groove and, due to the presence of the groove 4, no undue strain is exerted upon any part of the ring. By pressing against the side walls of the groove in which the ring is mounted the overlapping ends of the ring form a seal to prevent passage 25 of the gas. The presence of the groove 4 furthermore tends to equalize the outward pressure of the ring against the cylinder wall.

From the foregoing description it will be 30 apparent that the order in which the ring is given certain steps of treatment is unimportant, and that the invention is not restricted in its scope to the performance of all of the steps of the treatment in any definite order. I do not restrict myself to unessential features of the invention, but what I claim and desire to secure by Letters Patent, is:—

1. The method of making a piston ring 35 which consists in splitting a ring blank to form spaced overlapping ends, and then removing portions from the sides of the body portion of the material to form parallel side walls, and from the sides of the overlapping

ends until the ends have a combined width 50 equal to the width of the body portion.

2. The method of making a piston ring, which consists in splitting a blank to form spaced overlapping ends for a portion of the circumference of the blank, mechanically 55 pressing the overlapping ends together, and removing portions of the blank while the overlapping ends are mechanically pressed together to form a finished ring in which the combined width of the overlapping ends 60 when pressed together is equal to the remaining portion of the ring.

3. The method of making a piston ring, which consists in splitting a blank to form spaced overlapping ends, and removing a 65 portion of the material from the inner side of the blank opposite from the overlapping ends to equalize the radial pressure of the ring when compressed within a cylinder.

4. The method of making a piston ring, 70 which consists in splitting a blank to form spaced overlapping ends, removing a portion of the material from the blank opposite the overlapping ends to equalize the radial resiliency of the blank and removing portions 75 of the blank to form a ring in which the overlapping ends are held spread apart by the resiliency of the material in positions in which the combined width of the overlapping ends and the space between them is 80 greater than the width of the remaining portion of the ring, while the combined width of the overlapping ends when pressed together is equal to the width of the remaining portion of the ring. 85

5. The method of making a piston ring, which consists in splitting a ring blank to form overlapping ends for a portion of the circumference thereof; forming a groove in the inner periphery of the portion of the 90 blank opposite from the overlapping ends; pressing the overlapping ends together in opposition to the resiliency of the material; and finishing the ring to uniform width while the overlapping ends are held pressed 95 together.

STEPHEN D. HARTOG.
